Application September 21, 1945, Serial No. 617,874

7 Claims. (Cl. 315—5)

1

This invention relates to electronic tubes for operation at high radio frequencies. More particularly it relates to radially constructed velocity-modulated tubes for the production of electronic oscillations and for the amplification of electronic energy.

In conventional radio tubes the presence of the control grid in the stream of electrons directly affects the electrons emitted from the cathode. This results in the production of a charge-density modulation. It may be proven that this variation in space current, caused by the action of the grid, induces a similar variation of current in the grid circuit. When operating at low frequencies, these induced current variations which result in an instantaneous difference in the number of electrons approaching and leaving the grid are relatively unimportant because they are small and are approximately 90° out of phase with the grid voltage fluctuations and therefore cause no appreciable power loss. However, when tubes are operated at frequencies where the transit time of the electrons over the space current path becomes an appreciable portion of the time of one cycle, the induced grid current increases in magnitude and approaches the same phase as that of the grid voltage. This phenomenon causes the apparent shunt resistance of the grid circuit to vary inversely as the square of the operating frequency. Therefore, at high frequencies the use of conventional types of control grids results in such low shunt impedance and such high power losses that conventionally designed tubes become almost completely inoperative and useless.

A partial solution to this problem has been found in a velocity-modulated tube in which the electrode structures are so designed and constructed that the discharge current is velocity-modulated without the appearance of any appreciable charge-density modulation near the control electrode. In the conventional velocity-modulated tube electrons are emitted from the cathode, accelerated in a given direction, and are reacted upon by control electrodes associated with a resonant cavity or circuit, in such a manner as to alternately accelerate and decelerate the electrons. After the electrons pass the control electrodes and traverse a predetermined distance they become bunched in accordance with a particular waveform resulting from their difference in velocity. A second resonant cavity or circuit is provided and energized in proper phase to catch the bunched electrons and absorb energy from them.

Conventional velocity-modulated tubes may be

2

divided into two types; the reflex type and the direct electron beam type. In general, the former is used as an oscillator and the latter as an amplifier. Conventional reflex type tubes utilizing the same grids as bunchers and catchers, have the same buncher and catcher voltage and that voltage is such that the tube operates normally with an overbunched electron beam. Any reduction in this voltage would mean a sacrifice of output. The output in such a tube increases rapidly as the beam current is increased beyond the value of the starting current until overbunching occurs. The efficiency then follows a curve approximately proportional to the reciprocal of the beam current. Thus the efficiency is limited in such tubes since the optimum buncher voltage does not occur at the point of maximum output. Furthermore, in a longitudinally constructed tube the beam current is limited because of the relatively small emissive area which is due to the necessity of emitting electrons in a single direction. It is thus seen that the usual longitudinally constructed velocity-modulated tube is limited in its efficiency and output by the overbunching of electrons and by its limited beam current.

In tubes employing the emission of electrons from the cathode in a single direction, the means for altering the velocity of some of these electrons with respect to the others, the means for extracting energy from the bunched electrons, and the periods of the groupings are all interdependent. Also, all velocity-modulated tubes relying upon internal cavities for extracting the output from the tube are subject to critical adjustment and narrow operating frequency ranges since the tuning and spacing of the cavities are interdependent. The use of bellows for tuning these tubes causes a variation in the spacings of the elements and has proven to be impractical since the narrow variations they afford and their fragile construction necessitates extreme care even for small adjustments and for those due to the inherent construction of the cavity and the operation of its associated tube which require frequent readjustment.

Radially constructed tubes of the prior art have been limited in their use because they contain resonant circuits in the form of annular chambers designed to resonate at a particular frequency. As a result, these tubes also possess a fixed Q value (ratio of the amount of energy stored to the amount of energy lost per cycle) which makes their tuning a delicate and difficult problem. The advantages of the increase

in beam current obtained in such tubes is nullified by their complicated and fragile structure and by the necessity for delicate adjustments without affording a marked increase in the narrow operating frequency range of longitudinally constructed velocity-modulated tubes. This has caused such tubes to be infrequently used by the art.

It is an object of the present invention to provide a velocity-modulated tube which has a much larger output than the velocity-modulated tubes of the prior art.

It is also an object of the present invention to provide a velocity-modulated tube which is capable of operation over a wider range of frequencies than tubes of the prior art.

It is another object of the present invention to provide a velocity-modulated tube which, while capable of operation over a wider band of frequencies than tubes of the prior art, will also operate over a predetermined narrow range of frequencies at an increased efficiency as compared to the velocity-modulated tubes of the prior art.

It is another object of the present invention to construct a velocity-modulated tube which will produce a greatly increased beam current over tubes of the prior art.

It is a further object of the present invention to provide a velocity-modulated tube which is capable of being diverted from operation over a wide range of frequencies to operation over a desired narrow range of frequencies or vice versa by a substitution of the external cavity used without affecting any change in the actual or relative position of the electrodes within the tube.

Generally, this invention comprises a velocity-modulated tube whose electrodes are arranged as concentric cylindrical structures and which provides a radial stream of electrons which are velocity-modulated and are caused to deliver radio frequency energy to a resonant cavity which is external to the tube structure but electrically connected to the electrode structure of the tube.

Other objects, features, and advantages of this invention will suggest themselves to those skilled in the art and will become apparent from the following description of the invention taken in connection with the accompanying drawings in which:

Fig. 1 is a cross-sectional view of a reflex type velocity-modulated tube employing the principles of the invention with the grids shown diagrammatically; and

Fig. 2 is a diagrammatic representation of the external part of a cavity suitable for use in conjunction with the tube shown in Fig. 1.

Referring to Fig. 1, the reflex type tube is generally designated as 10. The general concentric cylindrical construction of the tube 10 may be properly appreciated by visualizing it as a figure of revolution about its longitudinal axis A—A.

The cylindrical cathode structure 11 has a cylindrical emitting surface 12 of strontium oxide, barium oxide, or other highly emissive material sprayed on a sleeve of nickel or other suitable material. Heater element 13 is contained within sleeve 12, disposed along longitudinal axis A—A of tube 10, and connected at one end to sleeve 12 and brought out to terminal 13a. External connection to cathode 11 is made by wire 14 brought out to terminal 14a. Heating current is supplied as by transformer 52 through leads connected to terminals 13a and 14a. Placed at either end of the sleeve 12 are the circular discs 15, 15, the diameters of which are equal and larger than that

of the sleeve 12 by an amount sufficient to enable them to serve collectively as beam forming electrodes. The buncher grid 16 is of slightly larger diameter than cathode structure 11 and is concentrically situated about it and is rigidly supported by the buncher grid structure 17. Likewise, concentrically situated about buncher grid 16 and of slightly larger diameter than that grid is the catcher grid 18 which is rigidly supported by the catcher grid structure 19.

Grids 16 and 18 are of similar construction. They are made of small wires of suitable material and arranged parallel to longitudinal axis A—A of tube 10 and spaced at discrete intervals around a circumference. Their respective supporting structures 17 and 19 are metallic cylindrical elements described hereinbelow in more detail. The wires of grids 16 and 18 are mechanically and electrically attached at their ends to their respective supporting structures. It is important that each individual grid wire of grid 16 be radially aligned with a corresponding grid wire of grid 18, that is, there must be an equal angular separation between each grid wire along the circumference of the respective supporting structures 17 and 19.

Outside of and concentric with grid 18 is a repeller plate 20, annular in shape and for maximum efficiency having a length parallel to axis A—A usually somewhat greater than that of cathode sleeve 12 and grids 16 and 18.

Concentrically located about all of the aforementioned electrodes and at a suitable distance radially outward from repeller plate 20 there is located the outer shell 21. Between the repeller plate 20 and the outer shell 21 is the metallic member 22 which serves the dual purpose of positioning the repeller plate 20 and of acting as an electrical conductor between the repeller plate 20 and the outer shell 21. Member 22 may be a series of small wire supports fastened to repeller plate 20 and shell 21 or may be a continuous washer or flange-like part connecting repeller plate 20 to shell 21 all along its circumference.

Buncher grid supporting structure 17 is sealed near one of its ends by glass to metal seal 23 through which heater element lead 13 and cathode lead 14 pass. At its other end it is reduced in diameter as at 24 and sealed by glass to metal seal 25. Seal 23 also mechanically secures the position of cathode connection 14, heater element 13, and cathode structure 11. At the other end the diameter of 17 is reduced thereby providing a smaller portion 24 which lends itself to a more easy sealing and facilitates the mechanical construction of the tube. This portion is of no electrical or other functional significance.

The buncher grid supporting structure 17 is sealed in a similar way to the catcher grid supporting structure 19 by the glass to metal seals 26 and 27. In a like manner, catcher grid supporting structure 19 is sealed to the outer shell 21 by glass to metal seals 28 and 29. It is noted that, in addition to their usual function of sealing the tube for evacuation, the glass to metal seals serve the important function of giving mechanical strength and rigidity to the entire structure of the tube. They also afford a convenient and permanent method of maintaining the proper spacing between the electrodes of the tube.

The electrode supporting structures 17, 19, and 21 should be of such material that they are good electrical conductors and have a coefficient of expansion equal to that of the glass used for making the seals. There are a wide variety of materials

possessing such a quality; an alloy of nickel, cobalt, and iron is one example of a material which has been widely used and found to give satisfactory operation.

The cavity 40 used in connection with the tube 10 is divided into two equal portions as shown in Fig. 2 and is connected between the buncher grid 16 and catcher grid 18 by a friction connection having electrical conductivity to the external portions 30 and 31 at one end of tube 10 and 32 and 33 at the other end of the structures 17 and 19 and friction fingers 41 and 42 on the cavity structure.

The action and significance of the cavity which should be used in conjunction with the present invention will be more fully described hereinbelow.

The actual and relative values of the potentials applied to the various electrodes of the tube 10 will differ in each application of the invention by an amount which will be more fully understood from the operating principles of the invention as explained in this specification. It may be stated, however, that equal potentials are applied to the buncher grid 16 and catcher grid 18 as by battery 50 and that these grids are positive with respect to the cathode structure 11 and that the repeller plate 20 is usually negative with respect to the cathode and the grids as by battery 51.

The cylindrical electron emitting surface 12 is much greater in area than that employed in conventional longitudinally constructed velocity-modulated tubes, and, therefore, it affords a much higher beam current which results in an equally increased output. This means that for a given output the tube 10 may be physically smaller than a longitudinally constructed tube and that the application of given potentials will result in a larger beam current.

In its more simple form, this invention is a device for converting direct current energy into radio frequency energy by alternately accelerating and decelerating a stream of electrons. The transit time between fixed points is utilized to produce an alternating electron stream which delivers power to a cavity resonator.

The radial electron stream emitted from the cylindrical cathode sleeve 12 is of uniform average velocity and proceeds toward the buncher grid 16 due to the accelerating voltage supplied by the cathode and the presence of discs 15, 15. As these electrons pass into the interaction gap 34 between the buncher grid 16 and the catcher grid 18, they encounter the strong alternating radio frequency field present in the interaction gap. This field tends to accelerate or decelerate the electrons dependent upon the potential of the field at the instant electrons enter it. Thus the radio frequency field causes the electron stream to suffer velocity-modulation. The electrons then proceed past the catcher grid 18 and enter into the drift space 35 between catcher grid 18 and repeller plate 20. In this drift space the electrons which are accelerated at one instant overtake electrons decelerated during the previous instant which causes a bunching of electrons to occur. As the electrons continue their transit and approach repeller plate 20, they encounter a negative or retarding direct current field caused by the potential on that plate from battery 51 and the electrons reverse their direction and achieve a more discrete bunching in the drift space 35 before they again reach the catcher grid 18. The phase of these reflected electrons is such that they reinforce the oscillations of the resonant cavity 43.

The bunches of electrons are grouped around

electrons which pass buncher grid 16 at the instant the radio frequency field is zero and decreasing. Since cavity 43 is provided to deliver radio frequency energy, these same electrons which made a first transit of the interaction gap 34 when the radio frequency field was zero and decreasing must make their second transit when this voltage is at a maximum negative value. The minimum beam current required to maintain oscillations is determined by the configuration of the cavity used, the cavity losses, the power required for bunching, and the circuit constants which determine the phase of the reflected electrons. Also, the impedance of the electron beam must be less than the shunt impedance of the cavity.

A decrease in the transit time of the electrons may be accomplished by increasing the repeller voltage which in turn increases the starting current.

After being reflected by the repeller plate 20, the electrons give up a certain amount of their energy to the catcher grid 18. Any electrons which pass the catcher grid during their second transit are collected by buncher grid 16 and their energy is dissipated as heat.

Since the voltage presented by the two grids 16 and 18 is the same for both transits, the phase difference of the voltage encountered by the electrons is entirely due to the electron drift time which is the time the electrons are in the drift space 35.

For a reflex tube of this type to produce oscillations:

$$\frac{(f)l}{V_0} - \frac{3}{4} = K$$

where

K is an integer,

f is the frequency of oscillation,

l is the length of the drift space, and

V_0 is the average velocity of the electrons.

It is pointed out that the results obtained from this relation should not be confused with the number of times the beam is bunched in the drift space.

Generally speaking, the beam may be bunched several times in the drift space of an amplifier if sufficient buncher voltage is available, but it is usually bunched only once in an oscillator. To maintain oscillations at a given frequency, it is required only that either the accelerator or repeller voltages be varied. A series of acceleration or cathode voltages exists which satisfy the phase relations for oscillations when the repeller voltage is fixed. Also several modes of oscillation are possible if the repeller voltage is varied and the acceleration voltage is fixed. It is, therefore, obvious that these effects may be combined and a change in acceleration voltage compensated for by a change in repeller voltage. However, the repeller voltage is usually the one varied since it requires no power when it is sufficiently negative to reflect the electrons that may have been accelerated to greater than the average velocity.

For oscillations to occur it is also necessary that the following equation be approximately satisfied:

$$\theta = N + \frac{3}{4}$$

where

θ is the average electron transit time across the drift space in cycles, and

N is any positive integer or zero.

A reduction in the acceleration voltage increases the transit time and an increase of the acceleration voltage decreases the transit time. For a linear potential variation in the drift space the transit time θ may be computed from the following equation:

$$\theta = \frac{500X}{\lambda\sqrt{V_c}}$$

where

θ is the average electron transit time across the drift space in cycle,
 X is the drift distance in centimeters,
 λ is the wavelength in centimeters, and
 V_c is the potential difference between the cathode and resonant cavity in volts.

The potential difference between the cathode and the resonant cavity is often referred to as the cathode voltages since the two are numerically equal. A simple relation between the cathode voltage and the operating frequency is obtained by combining the above two equations which yields the result that:

$$V_c = \frac{(2.5)10^5 X^2}{\left(N + \frac{3}{4}\right)^2 \lambda^2}$$

For any given tube the distance X is a fixed characteristic of that tube. Hence, for any given frequency, λ , there are a number of values of V_c which correspond to different values of N . The resulting oscillations for these different values of N are referred to as modes of oscillation. Also it is clear that for any given mode of oscillation V_c varies inversely as the square of the frequency.

The two separate sections 43, 43 of the external cavity used in conjunction with the present invention are made equal in length and the total length between their extremities is adjusted to be equal to one-half wavelength of the operating frequency less the length equivalent to the capacitative reactance within the tube. These two sections 43 of variable electrical length when combined with the tube structure act as a single one-half wavelength cavity having a maximum voltage at or near the center of the tube structure and a minimum voltage at either of its ends. Annular plungers 44 are provided to adjust the length of cavity 43.

This external cavity is excited by the interaction of the fringing radio frequency field with the electron stream bunched by initial passage through the fringing field and then caught by reflected bunches of electrons returning from the negative repeller or, if the repeller voltage should be less than that of the catcher grid, caught by secondaries from the repeller.

The proper choice of cavity design permits the application of the proper electrode voltages without any interference to the radio frequency field of the cavity or its mechanical tuning mechanism. In choosing this coaxial cavity its inner diameter is such that it slides over and makes good electrical contact with portion 30 of cylindrical grid structure 17 connected to buncher grid 16, and the inner diameter of its outer structure is such that it slides over and makes good electrical contact with portion 31 of cylindrical grid structure 18 connected to catcher grid 18.

It is emphasized that the Q of the resonant system is dependent upon the Q of its associated loaded circuit, and, hence, the type, shape, and size of the cavity employed. Consequently, the increased efficiency, output, and operating fre-

quency range, and the frequency stability of tubes employing this invention are primarily determined by the proper application by the user of the known principles pertaining to the characteristics of the loaded circuit employed. It should be mentioned that for operation over a wide range of frequencies the Q value of the loaded circuits should be low and that for operation over a narrow frequency range with high frequency stability, large output, and high efficiency, the Q value of the loaded circuits should be large.

The loaded shunt impedance is approximately proportional to the loaded Q value and it does not decrease appreciably as the load decreases; also, if the load is decreased until the output power approaches zero, the electrical tuning range does not decrease appreciably, but, as the load is decreased, the range of voltage over which the tube will oscillate increases. The starting current is inversely proportional to the shunt impedance of the cavity; therefore, any change in the configuration of the cavity which decreases the shunt impedance increases the minimum current required to maintain oscillations.

It is pointed out that the usual method of applying the potentials to the buncher grid 16 and the catcher grid 18 is by applying these potentials to the cavity in a conventional manner. In designing a cavity to operate with this invention it is a convenient and common practice to make an opening 45 approximately in the center of the portion of the cavity which connects to the external portions 32 and 33 so that the electrical connections may be made to the cathode connection 14a and heater element 13a. Electrical connection to the repeller plate 20 is made by any conventional type adapter located anywhere on the surface of the outer shell 21, or it may be made by direct connection of the conductor to the shell. The radio frequency output is extracted from the cavity 43 by means of a conventional single turn coupling loop 46 which is physically supported by the plunger 44.

Means for cooling the tube 10 may be provided by forcing air through appropriate pipes into each section of the resonant cavity and allowing it to escape through small slits 47 provided for this purpose and spaced around the circumference of the cavity and between the fingers 41 and 42.

These slits are longitudinal with respect to the cavity and should start at the end of the cavity where that end makes contact with the structure of the grids and extend a little beyond this contact surface. This type slit permits easy circulation of air and further serves to insure a good electrical contact between the cavity and the tube structure. If the output of the tube is especially large due to an increase in the demands upon it, the additional cooling necessary may be obtained by using external fans.

While there has been presented a detailed description of the construction and operating principles of a reflex type velocity-modulated tube employing the teachings of this invention, it is understood that the same type of construction and principles of operation equally apply to a direct electron beam type tube.

In the construction and operation of a direct electron beam type tube employing this invention there are no unusual or unexpected changes from that of a reflex type tube made in accordance with this invention. In this construction three concentric cylindrical grids will be used in place of the buncher and catcher grids of the reflex type tube and the repeller plate will be replaced

by an annularly constructed collector electrode similar in construction to the repeller plate above described. Two external cavities similar in design to the one used with the reflex type tube and concentrically arranged is used for operation with the direct electron beam tube. One cavity should be common to the inner and middle grids and the other connected to the outer grid. As in the case of the reflex type tube, the electrical length of each cavity is approximately equal to one-half a wavelength of the operating frequency and plungers are provided for adjusting its physical length.

In the direct beam type tube, the electrons which are radially emitted from the cathode pass into the interaction gap between the inner and middle grids where the presence of the strong electromagnetic field causes the electron stream to suffer velocity modulation. After the electrons pass the middle grid they enter into the drift space between the middle and outer grids where a more discrete bunching of the electrons is accomplished. Finally, the electrons pass the outer grid in such phase relation with the electromagnetic field of the cavity connected to that grid that they give up energy to this field and, hence, to the cavity. The electrons which succeed in getting past the outer grid are collected by the collector electrode and their energy is dissipated as heat.

While there has been here described what is at present considered to be the preferred embodiment of the invention, it will be obvious to those skilled in the art that various changes and modifications may be made therein without departing from the scope of the invention.

What is claimed is:

1. An ultra-high frequency tube of the reflex velocity modulation type comprising, a generally cylindrical vacuum-tight evacuated enclosure having glass end walls, two concentric cylindrical grids within said enclosure having conductive tubular extensions passing through said glass end walls, a cylindrical cathode within the inner grid, a cylindrical repeller electrode external to the outer grid, means for projecting a stream of electrons radially through said grids, and separate annular cavity resonator chambers external to the vacuum space and comprising a major part of the effective resonating space in the tube telescopically slidably over the outer surfaces of said tubular extensions and in electrical contact therewith.

2. An ultra-high frequency tube of the reflex velocity modulation type comprising a cylindrical cathode, first and second cylindrical grids, a cylindrical repeller electrode and a vacuum-tight evacuated cylindrical enclosure having glass end walls all assembled on a common axis, means for projecting a stream of electrons radially through said grids, conductive tubular extensions passing through said glass walls and connected to the ends of first and second grids respectively, and separate annular cavity resonator chambers external to the vacuum space and comprising a major part of the effective resonating space in the tube telescopically slidable over the outer surfaces of said tubular extensions and having a plurality of longitudinal slits forming resilient contact fingers adapted to engage said outer surfaces.

3. An ultra-high frequency tube of the reflex velocity modulation type comprising, a generally cylindrical vacuum-tight enclosure formed by a conductive tubular member having glass end walls

sealed thereto, two concentric cylindrical grids within said enclosure, conductive tubular extensions connected to each grid passing through said glass walls, a cylindrical cathode within the inner grid, a cylindrical repeller electrode external to the outer grid, means for projecting a stream of electrons radially through said grids, and a separate annular cavity resonator chamber at each end of the structure comprising a major part of the effective resonating space in the tube telescopically slidable over the outer surfaces of said tubular grid extensions, said resonator chambers having a plurality of longitudinal slits forming resilient contact fingers adapted to engage said outer surfaces and having adjustable annular tuning rings forming an electrical short circuit between said grid tube extensions.

4. An ultra-high frequency tube of the reflex velocity modulation type comprising, a cylindrical cathode, a pair of cylindrical grids external to said cathode, a cylindrical repeller electrode external to the grids and an evacuated metal cylinder having glass end walls external to and supporting the repeller electrode all assembled on a common axis, tubular extensions connected to and supporting the ends of each grid and passing through vacuum-tight seals in said glass end walls, means for projecting a stream of electrons radially through the grids, and annular cavity resonator chambers comprising a major part of the effective resonating space in the tube having resilient contact fingers telescopically slidable on the external surfaces of said tubular grid extensions, said resonator chambers including adjustable tuning rings forming an electrical short circuit between said grid tube extensions.

5. An ultra-high frequency tube of the reflex velocity modulation type comprising, a cylindrical cathode, a first cylindrical grid external to the cathode, a second cylindrical grid external to first grid, a cylindrical repeller electrode external to second grid and an evacuated cylindrical vacuum-tight enclosure having glass end walls, means for projecting a stream of electrons radially through said grids, conductive tubular extensions for first grid passing through vacuum-tight seals in said glass end walls, conductive tubular extensions for second grid external to the first extensions passing through said glass walls, and annular cavity resonator chambers comprising a major part of the effective resonating space in the tube external to the vacuum space and having resilient contact fingers telescopically slidably on the external surfaces of said tubular extensions, said resonator chambers including adjustable annular tuning rings forming an electrical short circuit between said first and second tubular grid extensions.

6. In an electronic oscillator for generating very high radio frequencies of the reflex velocity modulation type which includes means for establishing a radial flow of electrons and modulating said electron flow with a pair of coaxial grids supported by the inner tubular parts of two annular cavity resonators and having a cylindrical repeller electrode external to said grids; that improvement wherein the outer parts of said cavity resonators consist of enlarged annular chambers closed at their outer tubular ends and telescopically fitted to the external surfaces of said tubular inner parts of the cavity resonators.

7. The structure of claim 6 wherein said annular chambers are of substantially larger diameter than the walls of said inner parts of the cavity resonators whereby the overall length of

11

the tube is reduced and the cavity resonators made more nearly toroidal with consequent reduction in cavity losses.
